UNITED STATES PATENT OFFICE.

ERNEST T. McABEE, OF KANSAS CITY, KANSAS.

FLOOR-JOIST CONSTRUCTION FORM.

1,417,614.

Specification of Letters Patent. Patented May 30, 1922.

Application filed May 25, 1921. Serial No. 472,487.

To all whom it may concern:

Be it known that I, ERNEST T. McABEE, a citizen of the United States, residing at Kansas City, in the county of Wyandotte and State of Kansas, have invented certain new and useful Improvements in Floor-Joist Construction Forms; and I do declare the following to be a full, clear, and exact description of the invention, such as will 10 enable others skilled in the art to which it appertains to make and use the same, reference being had to the accompanying drawings, and to the figures of reference marked thereon, which form a part of this specification.

My invention relates to forms for concrete floor and joist construction and more particularly to an adjustable form dome for use in such work.

20 The principal object of the invention is to provide a dome used in conjunction with and supported on soffits or centering beams which may be readily adjusted to provide a form for the particular needs required in any 25 floor construction; that is, the same domes may be used in the construction of floor beams of various depths and side angles and various spacings between the beams.

In accomplishing these objects I have provided means for quickly adjusting the domes in position and for easily collapsing them for removal after the floor is formed.

Other features of my invention will be apparent by reference to the following description in connection with the accompanying drawings, wherein—

Fig. 1 is a perspective view of a concrete floor partially formed, showing the arrangement of domes constructed in accordance 40 with my invention on the soffits supported by shoring.

Fig. 2 is a transverse vertical sectional view of the finished floor illustrating two of the domes, one of which is collapsed for 45 removal.

Fig. 3 is a detail perspective view of a portion of a side section of the dome, illustrating the latching mechanism for securing the truss which supports the top sections of the 50 dome and the side sections together.

Fig. 4 is a detail perspective view of a portion of one of the trusses for supporting the top sections of the dome.

Referring more in detail to the drawings 55 by numerals of reference:

1 and 1' designate the opposite side sec-

tions, which, with the top sections 2 and 2', co-operate to form the wall portions of the dome. These are secured together by the trusses 3 and latching mechanism 4 to form 60 a completed dome, the details of which are hereinafter described.

The truss for supporting and securing the dome sections together comprises telescoping members consisting of angles 5 and 6, the 65 legs 7 and 8 of which overlap one with the other and are secured together by bolt and slot connections 9 and 10 respectively. Pivoted to the outer end of the angles 5 and 6 by bolts 11 are side supporting angles 12 70 and 13, braced with respect to the angles 5 and 6 by brace bars 14 and 15, which are secured to the lower ends of the angles 12 and 13 by bolts or fastening devices 16 and to the vertical legs 17 and 18 of the supporting angles 5 and 6 by bolt and slot connections 19 and 19' so that the side supporting angles 12 and 13 may be adjusted radially with respect to the top supporting angles 5 and 6 and so that the sides of the domes may 80 be adjusted to change the draft of the beams to be formed to support the floor. That is, with my preferred form, the angle which the side of the beam makes with the finished floor may be changed to suit the conditions 85 at hand by adjusting the bolt 19 in the slot 19' which, in effect, lengthens and shortens the braces 14 and 15, the side angles 12 and 13 pivoting on the bolt connections 16.

For securing the side sections 1 and 1' of 90 the dome together I provide the latch mechanism heretofore mentioned, which comprises angles 20 and 20', secured to the side sections 1 and 1' by fastening devices 21 and spaced apart to receive a side angle 12 or 95 13, as the case may be, of the supporting truss 3, which rests on a latch bar 22 pivoted at 23 to the angle 20' and which is retained in functional position by the spring latch 24, secured to the angle 20, as illustrated.

To key the truss to the side sections 1 and 1' to keep the sections from falling apart, I provide the wedge pins 25 which engage 105 openings 26 and 27 in the angles 20 and 20' and an opening 28 in the side angle of the truss 3 so that when the pin 25 is inserted, the parts are securely keyed together to prevent the forms from collapsing.

In constructing a floor of the character illustrated, the supporting soffits 29 are first 110 spaced in parallel alignment at a distance equal to the spacing of the beams 30 for

supporting the finished floor 31 and they are supported upon shoring or posts 32 of sufficient strength to support the finished floor until the concrete sets.

- 5 With the soffit boards 29 so spaced and supported, the domes may be adjusted there-between and moved into position. The domes are first adjusted for width through the medium of the trusses by lengthening or 10 shortening the supporting members and adjusting the telescoping angles 5 and 6 with respect to each other, which is readily permitted by their slot connections after which the angles 12 and 13 are adjusted to provide 15 the required draft for the beams. Then the side sections are secured together by inserting the pins 25, after which the top sections 2 and 2' of the dome are placed on the side sections as shown and the completed dome 20 placed upon the soffit in position.

After all the sections are placed and the floor set, the domes are removed by knocking out the pins 25 and releasing the latches, which permit the latch bars to drop, releasing the supporting trusses and dome sections 25 as shown in Fig. 2.

From the foregoing it will be apparent that a simple construction is provided and that the dome may be readily adjusted and 30 collapsed.

What I claim and desire to secure by Letters-Patent is:

1. In a dome having side sections and a top section, a longitudinally adjustable truss 35 member for supporting the top section, and a latch mechanism carried by the side sections for supporting the truss member.
2. In a dome having side sections and a top section, a truss member for supporting 40 the top section comprising telescoping members having bolt and slot connection, and a latch mechanism for securing the truss member to the side sections.
3. In a dome having side sections and a 45 top section, a truss member comprising telescoping members, side angles carried by the

telescoping members, and a latch mechanism carried by the side sections for engaging the side angles to secure the truss member to the side sections.

4. In a dome having side sections and a top section, a truss member comprising telescoping members having bolt and slot connections, side angles pivotally hinged to the ends of the telescoping member, brace bars 55 adjustably connecting the side angles to the telescoping members and means for securing the side angles to the side sections.

5. In a dome having side sections and a top section, a truss member for supporting the 60 top section and latch mechanism comprising a latch bar retained by a latch carried by the side sections for supporting the truss member.

6. In a dome having side sections and a 65 top section, a truss member having telescoping members, side angles carried by the telescoping members having openings therein, angles secured to the side sections having openings adapted to register with the 70 opening in the side angles and a pin for engaging in said openings for securing the side sections and truss member together.

7. In a dome having side sections and a top section, a truss for supporting the top 75 section having a pin engaging means, latch mechanism carried by the side sections having pin engaging means corresponding to the pin engaging means in the truss member, and a pin for engaging the pin engaging 80 means for securing the side sections to the truss member.

8. In a dome having side sections and a top section, a truss member for supporting 85 the top section, truss supporting means carried by the side sections comprising spaced angles secured to the side sections, a latch bar carried by one of the angles for supporting the truss and a latch carried by the other for securing the latch bar.

In testimony whereof I affix my signature.

ERNEST T. McABEE.
